LIQUID DISPENSING CONTAINER

Sidney S. Rand, New York, N. Y.

Application May 16, 1940, Serial No. 335,479

2 Claims. (Cl. 221—67)

My present invention relates to liquid dispensing containers, and more particularly to a novel and improved type of package-container adapted to dispense liquids, such as beverages, which hold gas under pressure in solution.

One of the primary objections to present methods of dispensing beer, for example, from the bottle or metallic can types of containers, is the fact that once the container has been opened the beer rapidly goes flat due to the carbon dioxide gases escaping from the liquid. Hence, it is not considered practical to put up beer in large size packages. Again, the opening of the metal can type of beer container is often a vexatious matter. Of course, where it is desired to employ a wooden container, of a size sufficiently small to be kept in the average home refrigerator, for packaging beer, it is considered impractical due to the inevitable bung hole and faucet. Yet beer on draught in the home refrigerator is a highly attractive and desirable objective for the beer industry.

Accordingly, it may be stated to be of the main objects of my present invention to provide a combined beer package and dispensing container which is readily made of wood, metal or even glass, and wherein the package is of a shape and size such that it readily fits into the average home refrigerator; the package being characterized by its inclusion of a liquid dispensing mechanism which has no protruding portions when in non-dispensing state.

Another important object of my invention is to provide a liquid container which may be fabricated of metal, wood, glass or any composition material; there being employed a liquid dispensing mechanism which normally does not extend beyond the container surface, and the dispensing mechanism being so constructed that it simultaneously provides a liquid outlet and an air inlet to the container interior.

Still another object of my invention is to provide a liquid container provided with a highly simplified dispensing mechanism which simultaneously provides an air port to the container interior and a liquid outlet upon actuation of the mechanism; and said container being capable of dispensing beverages whether alcoholic or not; oil; beverages containing gases under pressure and the like.

And still other objects are to improve generally the simplicity and efficiency of liquid packages of the dispensing type, and more especially to provide beer containers of the dispensing type

which are not only reliable and durable, but are easily and economically manufactured.

The novel features which I believe to be characteristic of my invention are set forth in particularity in the appended claims; the invention itself, however, as to both its construction and method of operation will best be understood by reference to the following description taken in connection with the drawing in which I have indicated diagrammatically a construction whereby my invention may be carried into effect.

In the drawing:

Fig. 1 is a plan view of the container, a portion on the right being broken away,

Fig. 2 is a sectional view taken along line 2—2 of Fig. 1, and looking in the direction of the arrows,

Fig. 3 is a sectional view taken along line 3—3 of Fig. 1, looking in the direction of the arrows, and showing the dispensing mechanism actuated to "open" position.

Referring, now, to the accompanying drawing, wherein like reference characters in the different figures designate similar structural elements, the numeral 1 denotes a hollow container of rectangular cross-section. While the container is shown as composed of metal, such as tin, yet it may, of course, be made of wood or even glass. The container may have a circular cross-section, if desired; it may also have any other desired configuration. The numeral 2 indicates the liquid contents of the container, and as stated previously, such contents may be beer, whiskey, wine, soda water, oil. In fact any well-known form of liquid which is dispensed from metal or wooden containers may be packaged in the container of my invention.

Assuming for the present case that the liquid 2 is a beverage which is carbonated, such as beer, there is provided a dispensing device which is illustratively located adjacent one end of the container. The dispensing mechanism is so constructed that it simultaneously provides an air vent, or port, to the container interior, and also provides an outlet for the liquid. The dispensing mechanism specifically consists of a tubular casing 3 whose upper end is joined to the upper face 1' of the container by an outwardly flared wall 4. The wall 4 may be struck out from the face 1', or its upper edge may be soldered to an opening in the face 1' for the purpose. The lower end of the casing is provided with a circular ledge or shoulder 5 whose diameter is smaller than the diameter of the cross-section of the main bore of the casing 3. The lower end of the casing is

provided with a cup-shaped valve seat 6. From Fig. 3 it will be noted that the bore 3' of the cylinder 3 communicates through the narrower passage 5' with the downwardly-facing seat 6. The casing 3 is preferably positioned centrally of the face 1', and may be spaced a small distance from the left edge of the latter as suggested in Fig. 1.

In the lower face 7 of the container there is provided a second valve seat 8 which is provided with a central opening 9 whose diameter may be equal to the diameter of the bore 5'. The valve seat 8 is preferably provided by stamping out a portion of the lower face 7 in the manner shown in Fig. 3. During the stamping process the margin of the valve seat 8 is provided with a recess 10, which is circular in shape. The purpose of this circular recess is to provide a circular ridge which is adapted to prevent the liquid issuing through the opening 9 from trickling along the lower face 7. Within the casing 3 there is disposed a valve stem 11 whose diameter is substantially smaller than the diameter of the bore 3', and is considerably smaller than the diameter of the bore 5'. The lower end of the stem 11 is secured to a convex male valve element 12 which is adapted to snugly fit the valve seat 6 when in the position shown in Fig. 2.

The upper end of stem 11 may be provided with a central bore 13, and the lower end of the bore bends at a right angle to the vertical portion thereof and provides an air communication into the bore 3'. This is shown more particularly in Fig. 3 wherein the horizontal section of the bore bears the numeral 14. The upper end of the stem 11 has an outer thread so that a manually-manipulable button 15 may be threadedly secured to the upper end of stem 11. The button 15 has an outer diameter which is equal to the diameter of the bore 3', and is provided with a central bore 13' which is in axial alignment with the bore 13. The bore 13', as shown in Fig. 2, terminates in a wider bore which is threaded so that it may co-operate with the outer thread on the upper end of stem 11. The upper end of bore 13' opens into the transverse groove, or slot, 20 provided in the upper end of button 15.

Fig. 2 shows that substantially half the body of the button 15 extends above the base of the shallow depression 4, while the other half is located for reciprocation within the bore 3' of casing 3. The slot 20 should have a sufficient depth so that when the finger of the operator is placed on the upper face of the button for depressing the same, in order to open the liquid outlet valve, there will be sufficient air space through the ends of the slot 20 so as to permit air to enter bore 13 and thereby travel through bores 13 and 14 into the bore 3'. It should also be noted that the upper end of button 15, in its normal closed position, is below the face 1'. This means that there is no protruding element in the upper face of the container which might serve as an obstacle when the container is placed, for example, in a home refrigerator.

The valve 12 is maintained snugly seated in its seat 6 by virtue of a coil spring 21 which is concentric with stem 11 and is compressed in position between the lower end of button 15 and the casing shoulder 5. The spring 21 normally presses up against the lower face of the button 15 and therefore maintains the valve 12-6 air-tight. The various elements of casing 3 and its associated elements of the valve may be all made of brass, and the lower end of stem 11 may, if desired, be threaded into the upper portion of

valve member 12. The latter may be hemispherical and of the exact configuration of seat 6.

Simultaneously with the actuation of button 15 to open the air inlet valve 12-6, there occurs the opening of the liquid outlet valve. The latter is provided by a male valve member 30 whose upper face has the convex configuration of the lower face of valve seat 8. The valve members 12 and 30 are rigidly coupled by a second stem 40 which may have the same cross-sectional diameter as the stem 11. The length of stem 40 will, of course, depend upon the distance between the seat 8 and the valve member 12. It is desirable that the valve seat 8 and valve member 30 be shallow so that there will be a minimum of liquid remaining on the bottom of the container. The opposite ends of stem 40 may be threaded so that they can be threadedly secured to valve members 12 and 30. By providing the threaded engagements between the stems 11 and 40 and their associated valve members it becomes easy to assemble or dis-assemble the valve mechanism.

It will now be seen that the air inlet valve and the liquid outlet valve are actuated in unison by depressing button 15. Assuming that the interior of the container has been filled with beer, the container can be placed in any home refrigerator without fear of its presenting any external obstacles to other articles in the refrigerator. Not only does the button 15 fail to extend beyond face 1', but the lower face of valve member 30 is contiguous with the face 7. Hence, in the normal, or closed position of the valve mechanism, the container externally presents the appearance of smooth walls. By pressing down on the button 15, seat member 12 is moved downwards, thereby permitting air communication into the interior of the container. As explained previously, the air path is through the ends of slot 20, into bores 13', 13 and 14, through bore 3' and through bore 5'.

By virtue of the fact that the finger of the operator is positioned over the slot 20 and above the upper end of bore 13', any liquid which may be ejected upwardly by the pressure within the container will be prevented from squirting upwardly. Whatever liquid does escape will collect within the shallow depression 4. As the air inlet valve 12-6 is opened, the liquid outlet valve 30-8 is opened and the liquid will smoothly issue through the opening 9, as shown in Fig. 3. It will, therefore, be seen that in the present invention it is not necessary to provide any special air vent as is common in prior metallic beer containers. Furthermore, the containers may be made up in any desired sizes since both valves are air-tight and hence do not permit the carbonated liquid within the container to become flat.

It is to be understood that the valve member 30, stem 40 and seat 8 may all be made of brass. Further, the seat 8 may be a separate element and have its ends soldered to face 7 if desired. It will also be noted that when the liquid in the container falls below the level of bore 14, there will be very little tendency for the liquid to squirt upwardly through bore 13' when the air valve is open.

While I have indicated and described a construction for carrying my invention into effect, it will be apparent to one skilled in the art that my invention is by no means limited to the particular construction shown and described, but that many modifications may be made without departing from the scope of my invention, as set forth in the appended claims.

What I claim is:

1. In a liquid container having substantially plane walls, a liquid dispensing mechanism comprising a liquid outlet valve in one wall, said outlet valve having its valve seat and closure element wholly in the plane of said one wall, an air inlet control valve projecting from a parallel, spaced wall into solely the container interior, and means responsive to actuation of said air inlet valve for actuating said liquid outlet valve, said means comprising a rod interconnecting the two valves, a depressible button operatively associated with the mobile element of the air inlet valve and said button being provided with a bore therethrough whereby to provide an air passage between said air inlet control valve and the exterior of said container.

2. In a liquid container of the type comprising spaced walls arranged in substantial parallelism, a liquid outlet control means comprising a valve

10 seat provided in the plane of one wall, a closure element normally seated in said seat and having a stem projecting into the container interior, means providing an air inlet chamber housing a portion of the stem, an air inlet control valve comprising a valve seat located wholly within the container interior and at the said chamber outlet, a closure element on said stem portion, means normally biasing said last element into seated position at said chamber outlet, said last closure element being provided with a depressible button, said button being located at the end of said stem and being substantially flush with the plane of the wall opposite to said one wall, said button being provided with an air inlet bore communicating with said chamber interior, and depression of said button actuating said stem thereby to unseat said first closure element.
